[57] CLAIM

The ornamental design for a bottle drainer, as shown and described.

DESCRIPTION

FIG. 1 is a perspective view of a bottle drain showing our new design;

FIG. 2 is a top plan view thereof;

FIG. 3 is a side elevational view thereof, the opposite side being a mirror image;

FIG. 4 is a front elevational view thereof, the opposite side being a mirror image;

FIG. 5 is a bottom plan view thereof;

FIG. 6 is a side elevational view thereof on a reduced scale; and,

FIG. 7 is a side elevational view thereof on a reduced scale.

The bottles and containers shown in broken lines in FIGS. 6 and 7 are for illustrative purposes only and form no part of the claim.
